COMBINED PARKING LAMP AND MIRROR

Herman Paine, Muncie, Ind.

Application November 22, 1950, Serial No. 13,091

Term of patent 14 years

(Cl. D14—6)

To all whom it may concern:

Be it known that I, Herman Paine, a citizen of the United States of America, residing at Muncie, county of Delaware, and State of Indiana, have invented a new, original, and ornamental Design for a Combined Parking Lamp and Mirror, of which the following is a specification, reference being had to the accompanying drawing, forming a part thereof wherein:

Figure 1 is a view in rear elevation of the combined parking lamp and mirror, showing my new design;

I claim:

The ornamental design for a combined parking lamp and mirror, as shown.

HERMAN PAINE.
